TREATMENT OF HYDROCARBON OILS

Ben B. Corson and George S. Monroe, Chicago,
Ill., assignors to Universal Oil Products Com-
pany, Chicago, Ill., a corporation of Delaware

No Drawing. Application October 30, 1939,
Serial No. 301,949

1 Claim. (Cl. 196—24)

This invention relates particularly to the treatment of hydrocarbon distillates of gasoline boiling range and more specifically to a method of treatment whereby the sulfur content of such distillates may be reduced without undesirably affecting other necessary properties. In some instances the treatment may improve the quality of the oils treated in other ways than reducing the sulfur content. For example, there may be reductions in actual and potential gum content, color, and antiknock value.

Desulfurization is one of the major problems confronting the petroleum industry since many crude petroleums, particularly those of a naphthenic or mixed base character, contain such quantities of sulfur that motor fuels made from them by straight distillation without cracking, and particularly those made by cracking their heavier distillates and residua, frequently contain so much sulfur that their use, without special treatment, is impossible since not only do the sulfur compounds impart a foul odor which is undesirable from a sales standpoint, but the sulfurous and sulfuric acids formed by oxidation of the gasolines in the cylinders of internal combustion engines frequently cause serious crank case corrosion, and the sulfur in the unburned gasolines corrodes feed lines, carburetor parts, etc. Although the limits of sulfur tolerance have been raised, due to better ventilation of crank cases, within the last few years, there are still definite limits to the total sulfur which is allowable in gasolines for use in internal combustion engines.

When the sulfur problem was first encountered in motor fuels, along with other problems peculiar to the treatment of cracked gasolines, such as improvement in color and gum content, the principal treatment in vogue was with sulfuric acid which was generally highly effective in improving the color and odor of straight run paraffinic and mixed base gasolines. But it was found that the use of sulfuric acid was seldom selective in improving any one property such as color, for example, if color was improved to a desired point, there was frequently large losses due to solution

and ester formation of olefinic compounds present. Similarly, attempts to desulfurize with sulfuric acid to meet the usual requirements of 0.10% sulfur caused extremely high losses and the formation of such compounds as sulfonic acids, sulfones, sulfur ethers etc. which remained dissolved in the gasoline, and were only partially removed by treatment with alkalis, clay filtration, or re-running of the acid-treated stocks. Desulfurization by the use of sulfuric acid therefore was found to have, and still has very limited application.

Among the methods which have been tried to effect selective desulfurization of cracked gasolines without adversely affecting other properties of such gasolines, particularly antiknock value due to removal or conversion of unsaturated compounds of relatively high antiknock value, is hydrogenation in the presence of catalysts under moderate temperature and pressure conditions. Heretofore, attempts to desulfurize cracked distillates by this method have generally met with failure because of the fact that the addition of hydrogen to unsaturated hydrocarbons apparently proceeded concurrently and excessively with the action of hydrogen on sulfur compounds of various types so that by the time the sulfur was reduced to the allowable maximum by the formation principally of hydrogen sulfide (evolved as a gas), the antiknock value of the gasoline had been seriously and permanently impaired by the saturation of olefinic hydrocarbons. This has been particularly notable in prior attempts to desulfurize gasoline boiling range liquids made by polymerization of the olefins in hydrocarbon gas mixtures containing sulfur compounds, since the olefins are readily hydrogenated, and as a rule their paraffinic counterparts have lower antiknock value. Another difficulty in prior attempts to desulfurize without serious loss of antiknock value has been the gradual, and sometimes rapid, deterioration of hydrogenation catalysts employed due to the formation of sulfides having reduced or no hydrogenating activity. It is with

improvements in desulfurizing sulfur-containing gasolines by means of hydrogenation that the present invention is concerned.

In one specific embodiment, the present invention comprises a process for desulfurizing gasolines containing both olefinic hydrocarbons and sulfur compounds which comprises subjecting the vapors of said gasolines mixed with relatively large amounts of hydrogen to contact with metal sulfide catalysts at temperatures within the approximate range of 250-450° C. and superatmospheric pressure of the order of 300 lbs. per square inch or higher while using relatively low liquid space velocities.

We have found that when using granular metal sulfides catalysts such as, for example, sulfides of nickel, copper, cobalt, iron, chromium, molybdenum, manganese, zinc, tungsten, etc., while observing the conditions of operation specified that cracked gasolines containing both sulfur compounds and olefins can be desulfurized to an extent so that they are readily marketable without adversely affecting antiknock value. As will be shown in later examples a relatively large excess of hydrogen over that necessary for effecting complete hydrogenation of the olefins and removal of sulfur is necessary, and if antiknock losses are to be minimized, the degree of olefin hydrogenation must be stopped at a definite point depending upon the composition of the gasolines treated in respect to sulfur and olefinic content.

While the scope of the present invention is not to be in any way limited by the theory expressed, it is considered to be possible that in the presence of a large excess of hydrogen and under the other limiting conditions of operation, the rate of desulfurization reaction increases out of proportion to the rate of olefin hydrogenation reaction so that effective sulfur removal is accomplished before undesirable olefin hydrogenation has occurred. Other possible factors are the rate of hydrogenation of various types of olefins, both normal and isomeric, but these are somewhat unpredictable, particularly in the complicated mixtures in which they occur in cracked gasoline. In some instances highly branched olefin hydrocarbons show greater antiknock after hydrogenation to the corresponding paraffins although this rule is by no means absolute. Relatively low liquid space velocities are preferable of the order of 0.5 to 5 depending upon the chemical and physical characteristics of the gasoline treated. It is to be noted that the temperatures and pressures employed are of moderate order.

Using the types of catalysts specified which vary in their degree of effectiveness so that while they may be used alternatively they are not in any sense exactly equivalent, substantially no difficulties are encountered with catalyst poisoning, and operations may be conducted over long periods of time before reactivation is necessary due to the deposition of carbonaceous materials. After such a point is reached, reactivation is readily practiced by passing air or other oxidizing gas mixtures over the spent catalyst to burn off the carbonaceous deposits. During this step some of the metal sulfide will be found to lose sulfur as sulfur dioxide and sulfur trioxide to form metal oxide which is later reduced to metal by hydrogen in a subsequent operating period and eventually sulfurized to metal sulfide by the sulfur in the gasoline. Whatever metal sulfide is oxidized to sulfate will be reduced to sulfide by the hydrogen present during the operating stages.

While it is preferred to start with sulfide catalysts in operating the process, it is comprised within the scope of the invention to start with metals which are gradually sulfurized during the process or deliberately sulfurized prior to the inception of the process by passing hydrogen sulfide or some other decomposable sulfur compound, either inorganic or organic, through the granular material. The catalytic materials may be employed on carriers or spacing agents of a relatively inert and usually siliceous refractory character. Besides frequently used siliceous carrying materials such as diatomaceous earth, clays, bentonites, montmorillonites, both raw and acid treated, crushed refractories etc., other carriers such as properly prepared alumina, chromium oxide, titanium oxide, cerium oxide, thorium oxide and zirconium oxide, and even high melting point salts such as calcium phosphate, aluminum phosphate, etc. may be used.

A convenient method of preparing suitable catalysts consists in precipitating metal hydroxides or carbonates on a support suspended in a solution of a metal salt to which a precipitant is added, the deposited compound being later reduced to metal which is later sulfurized, or the hydroxide or carbonate, etc. may be directly sulfurized without intermediate reduction. It is also comprised within the scope of the invention to form catalysts by precipitating metal sulfides directly upon suitable granular supports or by incorporating metal sulfides with finely divided supporting materials followed by pelletizing or otherwise forming of the particles of usable size. As a further alternative, preformed supports may be impregnated with metal salts and these composites sulfurized by any necessary method to produce a usable catalyst.

In the general operation of the process, sulfur-containing gasoline is vaporized, mixed with a relatively large excess of hydrogen or gases having a high hydrogen content, and the mixture is preheated to a temperature within the range previously specified and passed over granular catalysts at a rate determined by trial to produce the best results. It is to be recognized that each charging stock will require a different combination of operating variables to produce optimum results in respect to decomposition of organic sulfur compounds and hydrogenation of unsaturated hydrocarbons. The invention is not limited to any particular type of apparatus but may utilize any of those found to be suitable, either those of conventional type or of special design.

To illustrate the type of results normally obtainable in the operation of the present process, the following examples are introduced but without the intention of unduly limiting the scope of the invention in exact correspondence with the data presented.

EXAMPLE I

A gasoline was treated which had been produced by catalytically cracking a gas oil distillate from an East Texas crude oil. Vapors of the gasoline at a temperature of 350° C. (662° F.) were injected into hydrogen at the same temperature under a pressure of 900 lbs. per square inch and passed over a nickel supported nickel sulfide catalyst at a liquid space velocity of 1. The following tabulation shows the results obtained in a run made to determine the degree of olefin hydro-

genation which could be tolerated before appreciable loss in antiknock value occurred.

Period	Hours on stream	Bromine number	Hydrogenation, percent	Sulfur in product, percent	Octane number
Chg. Stk.		121		0.06	80.5
1	8	1	99.3	0.004	
2	16	3	97.7	0.007	
3	32	4	96.8	0.008	
4	40	2	97.7	0.008	
5	48	6	95.2	0.007	87.5
6	96		60.0	0.015	80.5

The catalyst employed in the run which furnished the above data was incompletely sulfurized at the outset of the run and therefore apparently had too high an activity so that excessive hydrogenation of the olefins occurred with a corresponding drop in octane number as shown after the fifth period of operation. As the catalyst became more highly sulfurized the octane number in the produce was regained while the sulfur was still being reduced notably. The following data shows the comparison of properties of the charging stock and the produce being produced at the end of the run:

	Chg. Stk.	Product
Ind. period, oxygen bomb test, minutes.	55	1,4440+
Copper dish gum, mg./100 cc.	60	11
A. S. T. M. gum, g./100 cc.	7	3
Color, Saybolt	Yellow	27
Color stability	Yellow	19
Doctor test	Positive	Negative.

EXAMPLE II

A run was made on a cracked gasoline produced from a California residuum. The gasoline was vaporized, mixed with hydrogen and passed over a nickel sulfide catalyst at a temperature of 350° C., varying hydrogen pressures, and a variable excess of hydrogen. The following tabulation of data was obtained in exploratory runs to determine the optimum conditions of operation:

Desulfurization of California cracked gasoline— Exploratory runs

Operating conditions:				
Temperature, °C.	350	350	350	350
Temperature, °F.	662	662	662	662
Hydrogen pressure, lbs./sq. in.	300	300	900	900
Liquid space velocity per hour	1.6	1.3	1.3	1.2
Bromine number:				
Original charge	63	63	63	63
Product	40	37	25	11
Sulfur, weight percent:				
Original charge	1.17	1.17	1.17	1.17
Product	0.25	0.12	0.16	0.06
Hydrogen, cu. ft./bbl.				
Hydrogen consumed by sulfur	29	33	32	35
Hydrogen consumed by olefin	171	189	278	385
Hydrogen consumed, total	200	222	310	420
Exit hydrogen from plant	200	1,535	325	1,860

The following tabulation of data summarizes runs using optimum conditions:

Desulfurization of California cracked gasoline, using optimum conditions as predicted from exploratory runs

5 Operating conditions:

Temperature, °C.	350	350
Temperature, °F.	662	662
Hydrogen pressure, lbs./sq. in.	300	300
Liquid space velocity per hour	1.3	2.7

10 Original charge:

Bromine number	63	63
Sulfur, weight percent	1.17	1.17
Octane number	72	72
Octane number+1 cc. T. E. L.	75	75
Octane number+3 cc. T. E. L.	77	77

Product:

Liquid yield, volume percent	96	98
Bromine number	21	47
Sulfur, weight percent	0.05	0.21
Octane number	69	73
Octane number+1 cc. T. E. L.	76	78
Octane number+3 cc. T. E. L.	81	81

Hydrogen:

20 Hydrogen consumed by sulfur, cu. ft./bbl. 35 30

Hydrogen consumed by olefin, cu. ft./bbl. 310 116

Hydrogen consumed, total cu. ft./bbl. 345 148

Exit hydrogen from plant, cu. ft./bbl. 1,405 1,865

1 Tetraethyl-lead.

2 67% hydrogenation of olefin

3 25% hydrogenation of olefin

4 96% Desulfurization.

5 82% Desulfurization.

Several points can be noted from the above tabulation of data, particularly that it was possible to reduce the sulfur content from 1.17% to 0.21% with only 25% olefin hydrogenation, the octane number being one point higher than in the original charge, possibly due to the removal of sulfur compounds which had a pro-knock tendency, and/or the selective hydrogenation of olefins whose paraffinic counterparts possess high antiknock value. The sulfur could be reduced to the negligible value of 0.05% with the loss of 3 octane number (72 to 69) with only 67% of olefin hydrogenation. The high susceptibility of the product to tetraethyl lead was also noticeable. In the runs given above the hydrogen excess was approximately 4 times that required for complete saturation of olefins and reduction of sulfur to hydrogen sulfide.

45 We claim as our invention:

A catalytic hydrogenation process for effecting substantial desulfurization of a gasoline containing both olefinic hydrocarbons and sulfur compounds and hydrogenation of olefinic hydrocarbons to an extent not materially reducing the anti-knock value of said gasoline, said process comprising subjecting vapors of said gasoline to contact with a heavy metal sulfide in the presence of an amount of hydrogen approximately four times that required for complete hydrogenation of said olefinic hydrocarbons and said removal of sulfur and at a temperature of approximately 350° C., under a hydrogen pressure of approximately 900 pounds per square inch and at a liquid-space velocity of not less than one and not more than two.
